JOSEF KRUPKA, AND COLESTIN KRUPKA, OF VIENNA, AUSTRIA.

WATER GLIDE SHOE.

Application filed May 31, 1928, Serial No. 281,782, and in Austria July 14, 1927.

This invention relates to water glide shoes in which during use the foot or leg is readily removably connected with a float, which comprises a skeleton covered with a watertight envelope or coat.

According to the present invention the envelope or coat together with a tubular extension, serving for the insertion and watertight packing of the foot and preferably extending to near the knee, consists of a single member or of a number of parts which are permanently united to a unit, the skeleton being inserted into the said envelope or coat by way of the tubular extension and is stretched out and braced up in the interior thereof.

Compared with other water glide shoes in which a skeleton, consisting of a number of parts which are screwed together, is covered with a watertight envelope or coat in the manner of a collapsible boat, the water glide shoe according to the present invention possesses the feature of great lightness and great stability, caused in that the individual parts of the skeleton, which is fitted together in the interior of the tubular or baggy closed envelope or coat, are propped up or stiffened with respect to each other and the envelope or coat, so that they may be of very small dimensions and do not require to be interconnected.

Therefore a pair of this kind of water glide shoes, which weigh approximately 13 pounds, can be comfortably carried in a knapsack and fitted together within a few minutes without the aid of any means which may be lost, while the known water glide shoes weight about 14 pounds and a large number of screws or the like are necessary for fitting up the skeleton.

Owing to the small weight of the water glide shoes it is possible to lift the legs and to step over, similar as it is the case when skiing, whereby it is also possible to readily get up after having fallen in the water.

One mode of carrying out the present invention is illustrated by way of example on the accompanying sheet of drawings in which:—

Figs. 1, 2 and 3 show the water glide shoe in side view, plan view and front view respectively.

Figs. 4 and 5 illustrate the two parts of the skeleton.

Fig. 6 is a perspective view of the connecting member of the skeleton-bars.

Fig. 7 illustrates the stiffening frame and the mode of arranging the bars.

Fig. 8 shows on an enlarged scale the mode of connecting the bars.

Figs. 9, 10 and 11 are detail views.

The glide shoe is formed by a float member, which encloses the foot or leg removably connected with it and is completely closed with the exception of the opening for inserting the foot or leg (Figs. 1 and 2). The float consists of a skeleton of wooden or metal bars or rods *a* or the like, which is fitted in the preferably baggy or tubular envelope *b* of a watertight material. The envelope is completely and permanently closed with the exception of the opening *c* (Fig. 2) for inserting the foot and the parts of the skeleton. The latter consists of two groups of bars or rods *s* and *s'*, in which the bars are arranged in the manner of an umbrella-frame (Figs. 4 and 5). A conical connecting member 1 (Fig. 6) forms the head piece of each group of bars *s* and *s'* and is provided with circumferentially disposed longitudinal grooves 2, in which are inserted the ends of the bars, the same being retained by a sleeve 3 (Figs. 4, 5 and 6). The connecting members 1 of the groups of bars *s* and *s'* form the ends of the glide shoe, which brace up or stiffen the bars with respect to the ends of the envelope. The bars *a* of the skeleton are supported by transverse frames 4, held apart and pressed against the envelope as well as secured the correct distance from one another. Every frame 4 is provided with grooves 5 for the arrangement of the bars *a* (Fig. 7). At corresponding places, the bars are furnished with notches or grooves 6 which are adapted to coincide with the grooves 5 of the frames 4 (Fig. 10), so that the bars *a* of the skeleton alternately embrace the frames at the bearing places and are immovably secured in position by the tension of the envelope.

Also the oppositely disposed bars *a* of the two groups of bars are braced up with respect to one another by the tension of the envelope and are connected with each other by means of sleeves 7. In order to produce the necessary strain, the ends 8 of the bars *a* are chamfered and a wedge 9 is passed through an opening of the sleeve 7 and disposed between the same, the envelope *b* of the glide shoe bearing against the said wedge 9 and secures the same in its position.

A plate or board 11 (Fig. 7), to which is

- attached the means for securing the foot, is detachably connected by means of rotatable hooks or the like with the two frames 4, which are disposed at the sides of the opening *c* and serve for the support of the skeleton-bars *a*. The forward bracket or belt 13, passing around the toes of the foot, is detachably connected with the foot-rest 14. The latter is provided with hooks 15 (Fig. 9) and the rear bracket or belt 13' is furnished with a forked end 16, a bolt 17 being arranged between the prongs of the latter and engages the hook-opening in the shutting position of the bracket or belt 13'. 10 A string 18 or the like is secured to the forked end 16 and passes outwardly through the opening *c* of the float, so that the means for securing the foot can be quickly disengaged by pulling on the string 18. 15 The string 18 is preferably connected with the closing belt, which serves for watertightly securing the tubular extension of the envelope to the leg, so that by opening this belt also the rear bracket or belt 13' is automatically disengaged and thus the connection between the foot or leg and the glide shoes is completely interrupted. 20 The fin- or pocket shaped extensions *i* of the envelope *b* of the float are formed by swinging flaps 19 (Fig. 11) which are braced up by wire-insertions and are connected to the envelope *b* of the float by means of ears 20 of a pliable material, so that the flaps 19 can easily fold down and again stand up, 25 and in the collapsed condition and the dismantled condition of the shoe take up very little space. 30 In the dismantled condition the glide shoes can be carried in a bag or the like, because they take up very little room. The glide shoes are fitted up very quickly without screw-connections and without the use of tools, this being carried out in the following manner:— 35 The envelope *b* is unfolded, the two groups of bars *s* and *s*¹ are fitted up by inserting the converging ends of the bars in the grooves 2 of the connecting member 1 and securing the same in position by the sleeves 3. The transverse frame 4, which is to be arranged near the end, is pushed between the bars (Fig. 4), and now the groups of bars *s* and *s*¹ are inserted into the envelope *b* by way of the opening *c*, the group 40 of bars *s* being disposed in the forward part of the envelope and the group of bars *s*¹ in the rear portion thereof. Thereafter the other transverse frames 4 are pushed between the bars of the groups of bars and 45 force apart the same towards the envelope *b*. The oppositely disposed ends of the bars are connected by the sleeves 7 and are braced up against the two ends of the shoe by means of the wedges 8 (Figs. 7 and 8). Finally 50 the means for securing the foot is inserted

and fixed, and the glide shoes are ready for use.

We claim:—

1. Water glide shoe comprising a collapsible skeleton, a watertight envelope for the latter, and a tubular extension on the envelope for the insertion and watertight packing of the foot, the said envelope together with the said extension consisting of a single member and the said skeleton being inserted into the said envelope by way of the tubular extension and is stretched out and braced up in the interior of the said envelope. 70

2. Water glide shoe comprising a collapsible skeleton, a watertight envelope for the latter, and a tubular extension on the envelope for the insertion and watertight packing of the foot, the said envelope together with the said extension consisting of a number of parts which are permanently united with one another and the said skeleton being inserted into the said envelope by way of the tubular extension and is stretched out and braced up in the interior of the said envelope. 80 85

3. Water glide shoe comprising a collapsible skeleton formed of groups of bars and of a connecting member to which the ends of the bars are detachably secured and which constitutes the end piece of the group of bars, a watertight envelope for the skeleton, and a tubular extension on the envelope for the insertion and watertight packing of the foot, the said envelope together with the said extension being in the shape of a single member and the said skeleton being inserted into the said envelope by way of the tubular extension and is stretched out and braced up in the interior of the said envelope. 90 95

4. Water glide shoe comprising a collapsible skeleton formed of groups of notched bars, of a connecting member to which the ends of the bars are detachably secured and which constitutes the end piece of the group of the bars and notched transverse frames cooperating with and bracing up the said notched bars when inserting the said frames, a watertight envelope for the skeleton, and a tubular extension on the envelope for the insertion and watertight packing of the foot, the said envelope together with the said extension being in the shape of a single member and the said skeleton being inserted into the said envelope by way of the tubular extension and is stretched out and braced up in the interior of the said envelope. 100 110 115

5. Water glide shoe comprising a collapsible skeleton formed of groups of bars and of a connecting member to which the ends of the bars are detachably secured and which constitutes the end piece of the group of bars, sleeves for connecting two oppositely disposed bar-ends of the group of bars, a transverse opening in each sleeve, a wedge 120 125 130

passed through the said opening, a watertight envelope for the skeleton, and a tubular extension on the envelope for the insertion and watertight packing of the foot, the said envelope together with the said extension being in the shape of a single member and the said skeleton being inserted into the said envelope by way of the tubular extension and is stretched out and braced up in the interior 10 of the said envelope.

6. Water glide shoe comprising a collapsible skeleton formed of groups of notched bars, of a connecting member to which the ends of the bars are detachably secured and 15 which constitutes the end piece of the group of bars and notched transverse frames co-operating with and bracing up the said notched bars when inserting the said frames, sleeves for connecting two oppositely disposed bar-ends of the group of bars, a transverse opening in each sleeve, a wedge passed through the said opening, a watertight envelope for the skeleton, and a tubular extension on the envelope for the insertion and 20 watertight packing of the foot, the said envelope together with the said extension being in the shape of a single member and the said skeleton being inserted into the said envelope by way of the tubular extension and is 25 stretched out and braced up in the interior 30 of the said envelope.

7. Water glide shoe as claimed in claim 4, further comprising means for securing the foot, within the skeleton, the said means consisting of a foot-rest, a member passing round the toes of the foot, hooks secured to the foot-rest, a forked member detachably inserted into the said hooks, a flexible member for the instep of the foot secured to the forked member, and a pull-member secured to the forked member and passing to the outside. 35

8. Water glide shoe as claimed in claim 6, further comprising means for securing the foot within the skeleton, the said means consisting of a foot-rest, a member passing round the toes of the foot, hooks secured to the foot-rest, a forked member detachably inserted into the said hooks, a flexible member for the instep of the foot secured to the forked member, and a pull-member secured to the forked member and passing to the outside. 40 45

9. Water glide shoe as claimed in claim 1, further comprising stiffened swinging flaps 50 connected with the envelope, for the purpose 55 specified.

In testimony whereof we affix our signatures.

JOSEF KRUPKA.
